pany, East Pittsburgh, Pa., a corporation of
Pennsylvania

Application February 20, 1937, Serial No. 126,852

14 Claims. (Cl. 191—39)

My invention relates, generally, to overhead trolley systems and it has reference in particular to an improvement in section insulators for overhead trolley systems.

It has been found in practice that the arc drawn by a current collector in passing from a live trolley wire to the insulating runner member of a section insulator is particularly destructive to the insulating material of the body of the insulator. The arc, being drawn along and beneath the insulating member, and having a great tendency to rise because of the currents of heated air about it, is maintained in intimate contact with the insulating member. The insulating material is thereby subjected to, and damaged by the heating effect of the arc, and in due time is so weakened that it either fails electrically by flashing over, or mechanically by rupturing through the section most subjected to heat of the arc. Such failures are particularly expensive, entailing not only great difficulty in replacing the section insulator, but also disrupting schedules and generally delaying traffic while the replacement is being made.

By utilizing the arc blowing effect of the magnetic field about a current-carrying conductor to downwardly repel an arc drawn by a current collector along the insulating member, the life of the insulating material may be greatly increased. Further, by positioning a number of metallic arc members along the insulating member, so as to break an arc drawn by a current collector into a plurality of short, serially related arcs, and by so directing the flow of the arc current between adjacent arcs, that it is substantially perpendicular to the direction of the arc, a plurality of locally concentrated arc repelling magnetic fields may be built up. The arc is thereby not only broken into a number of smaller arcs which may be more readily extinguished, but the metallic arc members provide a cooling medium for the arc stream, further aiding in its extinction. By increasing the resistance of the metallic path of the arc current through the arc members on the section insulator, the current flow in the arc may be materially limited, and further, by utilizing the arc blowing effect of the magnetic field set up by the flow of arc current in a resistance element, the thus already weakened arc may be more readily extinguished.

It is, therefore, generally an object of my invention to provide for materially reducing the harmful effects of an electric arc on the insulating member of a section insulator.

Another object of my invention is to provide

a renewable arc member for a section insulator, wherein a directed arc current flow is secured adjacent to the arc to materially increase the blowout effect of the magnetic field produced by the flow of arc current.

A further object of my invention is to provide metallic arc members for the insulating member of a section insulator, whereby an arc drawn by a current collector is broken into a plurality of serially related arcs.

Another object of my invention is to provide for directing the flow of an arc current in spaced metallic arc members on a section insulator so that the arc is repelled from the insulating member by the magnetic field set up by current flow in the members adjacent to the arc.

Still another object of my invention is to provide for materially limiting the flow of arc current on a section insulator, the current limiting means being disposed to repel the restricted arc from contact with the insulating member.

A yet further object of my invention is to provide for increasing the life of a section insulator by reducing the arc drawn by a current collector to a plurality of small, serially related arcs, such that the direction of arc current flow adjacent to each arc produces a magnetic field disposed to repel the arc from the insulating member.

A still further object of my invention is to provide arc extinguishing means for a section insulator which shall be simple and economical to manufacture, easily installed, and inexpensive to maintain.

Other objects of my invention will in part be obvious, and in part appear hereinafter.

My invention, accordingly, is disclosed in the embodiments hereof shown in the accompanying drawings, and comprises the features of construction, combination of elements, and arrangement of parts which will be exemplified in the construction hereinafter set forth, and in the scope of the application which will be indicated in the appended claims.

In a preferred form of my invention, the arc drawn by a current collector in passing from a live section of the trolley wire to the insulating member of a section insulator may be broken into a plurality of serially related arcs by auxiliary metallic arc members which are disposed along the insulating member of the section insulator. The path of the arc current through these auxiliary arc members may be so directed by metallic conductors associating or connecting spaced runner portions of the auxiliary arc members that the magnetic field about a con-

ducting path adjacent to an arc cooperates with the magnetic field about the arc to exert a downward repelling force on the arc. The arc is thereby not only repelled from the insulating member, greatly reducing the destructive heating effects of the arc on the insulating material of the member, but it is also stretched out and extinguished. The life of the insulating member is therefore greatly increased, and expensive replacements and traffic tieups are avoided.

For a more complete understanding of the nature and the scope of my invention, reference may be had to the following detailed description, taken in connection with the accompanying drawings, in which:

Fig. 1 is a side elevation view of a section insulator embodying the principal features of my invention;

Fig. 2 is a plan view of the section insulator of Fig. 1;

Fig. 3 is a sectional view of the section insulator of Fig. 1 taken along the line III—III of Fig. 1;

Fig. 4 is a sectional view of the section insulator of Fig. 1 taken along the line IV—IV of Fig. 1;

Fig. 5 is an end elevation view of an arc member, the side elevation view of which is shown in association with an end member in Fig. 1,

Fig. 6 is a side elevation view of a section insulator embodying another form of my invention;

Fig. 7 is a plan view of the section insulator of Fig. 6;

Fig. 8 is a sectional view of the section insulator of Fig. 6 taken along the line VIII—VIII of Fig. 6, and

Fig. 9 is a side elevation view of a portion of a section insulator showing an alternate form of the invention of Fig. 1.

Referring more particularly to Figs. 1 and 2, it may be seen that the reference numeral 10 denotes generally a section insulator comprising an insulating member 11, which may be constructed in any desired manner, comprising for example, an insulating material having a reinforcing core 12 as shown in Figs. 3 and 4. End members 13 and 14, which are adapted to support or position the section insulator in an overhead trolley system, may be secured in engagement with the insulating member 11. An arc member 15, removably associated with the end member 13, auxiliary arc members 16, disposed in spaced relation along the insulating member 11, and an insulating runner member 18 may be adapted to provide for smooth passage of a current collector along the section insulator. The runner member 18 may be secured to the body member 11 in any desired manner, such as by a connecting strap 19 and engagement with the runner portion of an auxiliary arc member 16.

In the form illustrated, the section insulator 10 is adapted for use in a loop system, wherein vehicular traffic passes along the line in one direction only, however, it is to be understood that the principles of the invention may also be to other forms of section insulators. In this instance, the section insulator is effective to materially repel an arc from the insulating member and extinguish said arc as a current collector passes along the insulator from left to right. The renewable arc member 15, which is disposed to be removably associated with the end member 13, may comprise generally a U-shaped channel member, as may be more clearly seen by referring to Fig. 5, 75 having a runner portion 20 to provide a wearing

and conducting surface for passage of a current collector (not shown). The upstanding sides 21 and 22 may be slotted for securing the member 15 in engagement with the end member 13 by means of the bolts 24 and 25, which are primarily adapted to secure the end member 13 in engagement with the insulating member 11. An upwardly extending transverse slot 28 in the arc member is disposed to form a downwardly extending arc tip 30 at one end of the member, 10 wherein the flow of current, as a current collector (not shown) leaves the arc tip 30, in moving along the insulator from left to right, must be directed in the downward direction.

To aid in disrupting an arc drawn by the current collector from the arc tip 30 as it passes along the section insulator, auxiliary metallic arc members 16 may be disposed in spaced relation along the body member 11 of the section insulator. In general, an auxiliary arc member 16 20 may comprise a metallic member having a substantially U-shaped cross-section, as may be seen by referring to Fig. 3, provided with a runner portion on the underside, and upwardly extending side flanges 33 and 34, adapted to be secured about the insulating member 11. An upwardly extending transverse slot 35 may be provided in the arcing member, extending through the runner portion and up into the side flanges 33 and 34, thus dividing the runner portion of the member 16 into a pair of related runner portions 36 and 37, associated by metallic conducting arms 38 and 39 on each side of the insulating member. By making the depth of the slot 35 substantially greater than the width, an upwardly looped metal conducting path, comprising the connecting arms 38 and 39, may be provided between the related runner portions 36 and 37. The side flanges 33 and 34 are adapted to be secured in engagement about the insulating member 11 at upper ends by the transverse bolt member 40, thus maintaining the auxiliary arc member 16 in operating relation on the body member 11.

As a current collector passes from the runner portion 36 to the runner portion 37 of an auxiliary arc member 16, the current of the arc sustained between the arc tip 30 and the runner portion 36 will follow the metallic conducting path 38—39 between the runner portions. As the current collector progresses still further along the section insulator, and passes to an adjacent arc member 16, an arc will be drawn from the runner portion 37 to the runner portion 36 of the adjacent auxiliary arc member. It may be seen, therefore, that in general, the direction of current flow adjacent to the arc drawn between the members is substantially perpendicular to the axis of the arc, thus resulting in a magnetic field between adjacent arc members which tends to force the arc downward, not only repelling it from the insulating member, but exerting a blowout force to extinguish the arc itself.

In another form of my invention, which is illustrated in Figs. 6, 7, and 8, an elongated coiled 65 resistance element comprising similar sections 45 and 46 may be disposed in divided relation adjacent to opposite sides of the insulating member 11, and associated in series circuit relation with an arc member 15 and a U-shaped auxiliary 70 arc member 47, which may be provided with a runner portion 48 on the underside, similar to the runner portion 36 of the auxiliary arc member as shown in Fig. 3. The sections 45 and 46 of the resistance element may be secured to the 75

insulating member 11 in any desired manner, such as by positioning the auxiliary arc member 47 in spaced relation to the arc member 15 with upstanding sides 49 and 50 about the insulating member 11 and the sections 45 and 46 of the resistance element, and securing them in engagement by a transverse through bolt 51, as illustrated in Fig. 8. A similar U-shaped clamp member 47 may be positioned in engagement with the other ends of the coiled resistance sections to aid in securing them firmly to the insulating member 11.

As a current collector proceeds along the section insulator from left to right, the current flow in the arc tip 30 of the arc member 15 is directed downwards as the current collector leaves the arc tip, thus building up a downwardly repelling magnetic field which acts to extinguish any arc drawn therefrom by the current collector. When the current collector makes contact with the auxiliary arc member 47, current will be drawn through the coiled resistance element sections 45 and 46, thus reducing the arc current drawn from the arc tip 30, but still maintaining the arc from the arc tip 30 as the auxiliary arc member 47 will be at a substantially lower potential than the arc tip 30, because of the resistance drop in the coiled resistance element sections 45 and 46. At the same time, a concentrated magnetic field will be built up by the current flowing through the sections of the coiled resistance element. As the current collector leaves the auxiliary arc member 47 and moves on to the insulating runner member 18, the arc it draws will be substantially limited by the resistance of the coiled element sections 45 and 46, and will further be subjected to the concentrated magnetic field set up by the plurality of turns in the resistance element sections. The arc drawn, therefore, is not only limited by the resistance element, but is broken into a pair of related arcs, each of which is subjected to the blowout effect of separate magnetic fields, thus facilitating ready extinction of the arcs.

Fig. 9 shows an additional form of auxiliary arc member which may be used in a similar manner to the arc members 16 of Fig. 1. Generally, it may comprise a U-shaped member 53 having a runner portion 54 and upstanding side flanges 55 which are adapted to encompass the insulating member and be secured in engagement at the upper ends by a bolt 57. These arc members are adapted to be positioned on the insulating member in spaced relation and are associated in paired relation by resistance elements 58, disposed to provide a path of relatively high resistance for an arc current between the auxiliary arc members of a pair.

As a current collector traverses the section insulator, an arc will be drawn from the arc tip 30 of the renewable arc member 15. As the current collector further traverses the section insulator, the arc will be drawn to the first auxiliary arc member 53, and as the current collector reaches the second arc member, the arc current will follow the conducting path through the first arc member 53, resistance member 58 and the second arc member 53. In this manner, the direction of current flow adjacent an arc will be substantially perpendicular to the axis of the arc, and a downwardly repellant magnetic field will therefore be reactive on the arc to extinguish it. The resistance member 58 serves to further weaken the arc by limiting the flow of arc current, thus further aiding in the arc extinction.

By incorporating a number of pairs of arc members in spaced relation along a section insulator or other insulating fixture, the desired arc extinguishing characteristics may be obtained.

It may, therefore, be seen that by my invention I have provided means for the protection of the insulating member of a section insulator which may readily be applied even to insulators already in service. It is further, not only simple and inexpensive to manufacture, but easily installed and economical to maintain, effectively repelling an arc drawn by a current collector from contact with the insulating member and substantially increasing the life of the insulating material.

Since certain changes may be made in the above description and different embodiments of the invention without departing from the spirit thereof, it is intended that all the matter shown in the accompanying drawings or contained in the above description shall be considered as illustrative and not in a limiting sense.

I claim as my invention:

1. The combination in a section insulator for an overhead trolley system of, an insulating member, end members adapted to position the insulating member, a transversely slotted current directing arc member associated with an end member, and means including an auxiliary runner arc member for providing a conducting path for an arc current cooperative with said arc member to magnetically repel an arc from the insulating member.

2. A section insulator for an overhead trolley system comprising the combination of an insulating member, support means secured to the ends of the insulating member, and a plurality of transversely slotted metallic runner members disposed in spaced relation on the insulating member to provide upwardly looped paths for the current of an arc drawn between said runner members by a current collector, the magnetic field about said paths being disposed to downwardly repel an arc from the insulating member.

3. A section insulator comprising, in combination, an insulating member, end members adapted to position the insulating member in operating relation, a renewable arc member associated with an end member and provided with an upwardly extending transverse slot disposed to form a downwardly projecting arc tip, and a plurality of upwardly transversely slotted metallic runner members disposed on the insulating member in spaced relation adapted to break an arc drawn by a current collector into a plurality of serially related arcs and provide a magnetic field disposed to repel an arc from the insulating member.

4. The combination in a section insulator for an overhead trolley system comprising, an insulating member, end members adapted to position the insulating member, a transversely upwardly slotted renewable arc member associated with an end member, a renewable insulating runner member, an auxiliary metallic arc member associated with the runner member, and arc current conducting means of relatively high resistance in series circuit relation with the renewable arc member and the auxiliary arc member adapted to limit the current in an arc drawn by a current collector and provide a magnetic field disposed to downwardly direct an arc drawn by a passing current collector.

5. The combination in a section insulator of, an insulating strain member, end members adapted

- to secure the insulating member in an overhead trolley system, a renewable slotted arc member associated with an end member, said slot being disposed to provide a downwardly directive path 5 for an arc current adjacent the end of the arc member, and a plurality of auxiliary metallic arc members disposed along the insulating member in association with a runner member to provide a plurality of serially related arc gaps, said auxiliary 10 arc members being upwardly slotted to provide a looped path for an arc current, thereby providing an arc repellent magnetic field on transition of a current collector.
6. A section insulator comprising, in combination, 15 an insulating strain member, end members in association with the strain member, an arc terminal member associated with an end member having an upwardly extending slot adapted to provide a downwardly directive path for an electric arc current, and a plurality of spaced metallic runner members associated in paired relation by integral conducting portions adapted to provide upwardly looped current paths for an arc current thereby providing a magnetic field 20 disposed to downwardly direct an electric arc drawn in the passing of a current collector along the insulator.
7. The combination in a section insulator for an overhead trolley system of, an insulating member, end members adapted to secure the insulating member in operating relation in the overhead system, a renewable metallic arc member associated with an end member and provided with an upwardly extending transverse slot to form a 25 downwardly extending arc tip, a renewable metallic runner member disposed in spaced relation to said arc tip, and arc current conducting means disposed in series circuit relation with the runner member and the arc member, comprising a plurality of turns of a metallic ribbon of relatively high resistance positioned along the sides of the insulating member adapted to limit an arc current and produce a magnetic field disposed to repel an arc from the insulating member.
- 40 8. A section insulator comprising, in combination, an insulating member, end members to support said member, an arc terminal member having an upwardly extending transverse slot associated with an end member, and a transversely slotted arc member comprising a pair of spaced metallic runner portions with upstanding integral looped connector portions about the insulating member, said arc member being in spaced relation with the arc terminal member to provide a metallic path 45 for an arc current and produce an arc repellent magnetic field.
- 60 9. The combination in a section insulator for an overhead trolley system of, an insulating body member, end means adapted to position the body member in an overhead system, a transversely upwardly slotted arc member associated with an end means for directing the path of an arc current, a renewable metallic runner arc member disposed in spaced relation with said slotted arc member, and means comprising a metallic path for an arc current disposed in series circuit relation with the end means and the renewable arcing member to

provide a relatively substantial voltage drop between the end means and the runner arcing member and provide an arc repelling magnetic field.

10. A section insulator for an overhead trolley system comprising, in combination, an insulating body member, end members adapted to secure the body member in operating relation, and means including a plurality of transversely slotted metallic runner members adapted to break an arc drawn by a current collector into a plurality of 10 serially related arcs, said members being slotted to provide an upwardly looped path for the arc current and operable to produce an arc repelling magnetic flux.

11. A section insulator for an overhead trolley system comprising, in combination, an insulating member, end members adapted to position the insulating member, and a metallic runner member transversely slotted to provide an upwardly looped path for the current of an electric arc drawn by 20 a passing current collector, the magnetic field about the current path being disposed to downwardly repel the arc from the insulating member.

12. The combination in a section insulator of an insulating member, end members adapted to 25 position the insulating member, an arc terminal member upwardly slotted to provide an electric arc current path substantially perpendicular to the axis of the insulator associated with an end member, a plurality of runner members disposed 30 in spaced relation along the insulating member, and metallic conducting paths integral with the runner members disposed to associate the runner members in paired relation and to provide upwardly looped metallic paths about the insulating 35 member for an arc current whereby a magnetic field repellent to an arc along the insulating member is provided while said arc current flows.

13. The combination in a section insulator of an insulating strain member, end members 40 adapted to position the strain member, an upwardly transversely slotted arc member associated with an end member, a metallic runner arc member disposed in spaced relation with said slotted arc member, and arc controlling means 45 including an elongated coil of relatively high resistance disposed to be positioned in divided relation about the insulating member in series circuit relation with the slotted arc member and runner arc member to provide a potential differential 50 between said members and a magnetic field disposed to downwardly repel an electric arc when an arc is drawn by a passing current collector.

14. A section insulator comprising, in combination, an insulating strain member, end means adapted to position the insulating member, a plurality of metallic arc members having upstanding sides disposed in spaced relation along the insulating member to provide spaced metallic runner portions, and connector members of relatively 60 high resistance disposed to associate said upstanding sides to connect the auxiliary arc members in paired relation for substantially limiting the flow of arc current between pairs of auxiliary arc members and providing upwardly looped arc 65 current paths therethrough.

CHARLES C. WHITTAKER.
